UNITED STATES PATENT OFFICE.

JAMES BISHOP, OF HULL, CANADA, ASSIGNOR OF ONE-HALF TO JOHN PAINTER, OF SAME PLACE.

PAPER-PULP SCREEN.

SPECIFICATION forming part of Letters Patent No. 581,671, dated April 27, 1897.

Application filed December 9, 1896. Serial No. 615,071. (No model.)

To all whom it may concern:

Be it known that I, JAMES BISHOP, of Hull, in the Province of Quebec, in the Dominion of Canada, have invented certain new and useful Improvements in Paper-Pulp Screens; and I do hereby declare that the following is a full, clear, and exact description of the same, reference being had to the accompanying drawings, in which—

10 Figure 1 is a top view of my pulp-screen, the screen partly broken away to show the inclined divisions in the trough; Fig. 2, a side elevation of the same; and Fig. 3, a section on line X X, Fig. 1, the screen shown as entire.

15 My invention has for its object to prevent the meshes or perforations in a paper-pulp screen from becoming clogged with pulp by passage of air through one-half the meshes in alternate and opposite directions, and also 20 to prevent the accumulation of "strings" of solidified pulp hanging from the bottom of the screen, which, dropping into the vat, do not amalgamate with the semifluid pulp, but cause irregularity and breaks in the paper 25 when the pulp is made into paper.

My invention consists of a bottomless trough divided by one or more vertical longitudinal partitions and inclined transverse partitions, the alternate rows of spaces formed 30 by the divisions inclining in opposite directions, a screen within said trough and above said divisions, and means for reciprocally agitating the trough, so that when moving in one direction the correspondingly-inclined series of divisions will force the air upward 35 through the meshes and the reversely-inclined series of divisions will suck through the meshes above them, and when the trough moves in the opposite direction a vice-versa 40 air action through the screen-meshes is produced.

A is the vat, which receives the screened pulp, and A' an opening in the side to remove the pulp.

45 B is a bottomless trough mounted partly within and partly above the vat, preferably by a spring C at each end, the ends of the springs thickened to rest in bearings D, secured to the corner-posts E, which support 50 the vat, so that the trough can be shaken re-

ciprocally in a short tremulous motion by suitable mechanism.

The trough B is divided longitudinally by one or more vertical partitions B' and subdivided by transverse partitions B². One half 55 of the number of said partitions B² incline in one direction and the other half in the opposite direction, said partitions and divisional spaces forming an open bottom to the otherwise bottomless trough.

60 F is a screen lying on the partitions, and through the meshes or perforations of said screen the pulp passes into the vat below when the trough is agitated reciprocally.

The trough is reciprocated by any suitable 65 mechanical means, preferably by pitmen K K', one at opposite sides, connected to eccentrics L L' on a shaft P, journaled in bearings supported by the end posts E and carrying a cone-pulley M. A cone-pulley N is journaled below the same and carries a fly-wheel 70 R, and said pulleys are connected by a belt Q for adjusting the speed.

The trough above the screen is filled with the semiliquid pulp to be screened and the 75 trough agitated reciprocally. When the trough moves in one direction, the air in spaces G, which incline in that direction, will move upward and clear the perforations or meshes covering said divisional spaces, and the other 80 divisional spaces, H, will cause suction through the perforations or meshes above them and prevent the formation of strings of solidified pulp accumulating on the bottom of the screen and dropping into the vat, to the 85 injury of the paper when made.

When the trough is reciprocated in the opposite direction, the divisional spaces G will suck and the divisional spaces H blow through the meshes of the screen. The sucking spaces 90 become blow-spaces at the return motion of the trough.

The trough may be divided into inclined divisional spaces by any preferred arrangement of partitions, and I do not limit myself 95 to the series shown and described herein.

I claim as my invention—

1. A paper-pulp strainer, comprising a bottomless trough divided by a vertical longitudinal partition B', and transverse partitions 100

B², on opposite sides thereof, the partitions on one side of the longitudinal partition sloping in an opposite direction to the partitions on the other side, a screen F, covering the 5 divisional spaces within the trough, and means for reciprocating the trough longitudinally in a horizontal plane, as set forth.

2. A paper-pulp strainer having a bottomless trough divided by partitions into rows 10 of spaces sloping in opposite directions longitudinally of the trough, said rows separated by a vertical partition, a screen covering the divisional spaces, a vat below said trough, and means for reciprocating the trough in a

horizontal plane relatively to the sloping 15 spaces, as set forth.

3. In a pulp-strainer, the combination of a vat to receive the screened pulp, a bottomless trough divided by partitions sloping in opposite directions, a sieve or screen covering 20 the divisional spaces, and means for reciprocating the trough in a horizontal plane relatively to the direction of the slope of the partitions, substantially as set forth.

JAMES BISHOP.
